UNITED STATES PATENT OFFICE.

NORRIS E. GOODRICH, OF BATTLE CREEK, MICHIGAN, ASSIGNOR TO SANITARIUM AND HOSPITAL EQUIPMENT CO., OF BATTLE CREEK, MICHIGAN.

ARC-LAMP APPARATUS.

Application filed August 1, 1927. Serial No. 209,891.

The main objects of this invention are:

First, to provide an improved arc lamp apparatus especially adapted for use in therapeutic light equipment.

Second, to provide an apparatus of this character which has comparatively few parts and these of simple durable form and convenient arrangement.

Third, to provide an improved arc lamp apparatus in which a plurality of lamps are connected in series and provided with feeding means common to all of them.

Objects pertaining to details and economies of my invention will appear from the description to follow. The invention is defined in the claims.

A structure embodying the features of my invention is clearly illustrated in the accompanying drawing, in which:

20 Fig. 1 is a fragmentary view partially in section on a line corresponding to line 1—1 of Figs. 2, 3 and 4 of a therapeutic lamp apparatus embodying the features of my invention.

25 Fig. 2 is a detail view partially in vertical section on a line corresponding to line 2—2 of Figs. 1 and 4.

Fig. 3 is a fragmentary view partially in horizontal section on line 3—3 of Figs. 1 and 2.

30 Fig. 4 is a detail view partially in section showing details of the carbon supporting and feed means.

Fig. 5 is a fragmentary view of electrode screen and its supporting means.

Fig. 6 is a detail vertical section through one of the supporting arms.

Fig. 7 is a horizontal section on line 7—7 of Fig. 2 showing further details of the supporting means.

Fig. 8 is a diagrammatic view illustrating the series connections for the lamps and their control or feed means.

Referring to the drawing, 1, 1 are the supporting standards of the frame which is preferably that shown in my concurrent application on therapeutic light apparatus.

The reflector 2 is elongated and of curved cross section, its supporting arms 3 being adjustably mounted on the standards 1. The standards have adjustable uprights 4.

I provide a plurality of lamps, two being illustrated in the accompanying drawing, their bottom electrode holders 5 being supported by the rods 6 and 7 depending within

the reflector. The bottom electrode or carbon 8 is adjustably supported in the holder by means of the set screw 9.

The holder 10 for the top carbon 11 is carried by a feed or clutch rod 12 mounted for vertical adjustment through the plate 13. An insulating block 15 is arranged on this plate and supports the clutch 16.

A pair of supporting posts 14 are disposed to project upwardly from the housing and have cross pieces 17 connected by the longitudinal bar 18. The rods 6 and 7 are insulated from the bottom plates 13, see Fig. 4.

On the cross pieces 17 I mount a rockshaft 19 having arms 20 which are connected by the links 21 to the feed clutches 16. This rockshaft also carries arms 22 and 23, the arms 23 being connected to the dashpot cylinder 24, the plunger 25 of which is indicated by dotted lines in Fig. 2 and carried by the rod 26.

The arm 22 is connected to the armature 27 of the series coil or solenoid 28. Thus arranged the clutches 16 are actuated in unison from a single solenoid.

35 In Fig. 3 29 represents the circuit cable, one of the circuit wires being connected to a post 30 and the coil connection being indicated at 31. From the coil to post 32 a connection is made having therein a resistance element 33. The post 32 is connected by the connection 34 to the post 35 on the clutch rod 12 of one of the lamps.

40 The holder supporting rod 7 of the first lamp of the series is connected by the wire 36 and the flexible connection 37 to the feed rod of the second lamp, while the supporting rod 7 of the second lamp, which has an extension 7' at its upper end, is connected by the adjustable resistance coil 38 to the second circuit wire as indicated in Fig. 3. The result 45 of this connection is that I am able to dispense with shunt solenoids, the carbons are uniformly fed and one lamp of the series does not rob another.

45 The operating parts are mainly within the housing 39 mounted on the reflector. This housing comprises a body portion which is secured to the reflector and a top 40 which is secured to the cross piece 18 by means of 50 the screws 41. When these screws 41 are removed the top 40 may be removed to afford access to the mechanism within the housing.

55 I provide screens for the carbons consisting of bottom plates 42 having central holes 55

43 therein to receive the bottom electrode. A top band 44 is provided, the bottom plate and the band being connected by the side pieces 45 which are extended into spring arms 46 above the band 44. These spring arms have inwardly projecting fingers 47 engageable with the adjustable collars 48 on the carbon holder supporting rods 6 and 7. Spring clips 49 are carried by the spring arms 46 to engage these rods.

10 49 The screen 50 is mounted between the bottom 42 and the band 44. The carbons are thus enclosed so that the sparks and débris fall within the screen.

15 I have illustrated and described my improvements as I have embodied the same in therapeutic lamps. I have not attempted to illustrate or describe various modifications and adaptations which I contemplate as I believe these disclosures will enable those skilled in the art to embody or adapt my improvements as may be desired.

20 Having thus described my invention what I claim as new and desire to secure by Letters Patent is:

25 1. The combination of an elongated cylindrically curved reflector mounted for tilting adjustment on an axis adjacent one edge thereof, a plurality of lamps each comprising a pair of bottom carbon supporting rods suspended within said reflector and provided with a lower carbon holder, top carbon holders provided with feed clutch rods disposed through said reflector, feed clutches coacting with said clutch rods on the outside of said reflector, a rockshaft provided with arms, links connecting said arms to said feed clutches, a dashpot operatively connected to said rockshaft, a series coil armature operatively connected to said rockshaft, a series coil cooperating with said armature, series connections for said lamps including a resistance coil interposed between the said series coil and the first lamp of the series, an adjustable resistance coil in the circuit connection for the last lamp of the series, and a housing for the parts mounted on the outside of said reflector.

30 2. The combination of a reflector, a plurality of lamps each comprising a pair of bottom carbon supporting rods suspended within said reflector and provided with a lower carbon holder, top carbon holders provided with feed clutch rods disposed through said reflector, feed clutches coacting with said clutch rods on the outside of said reflector, a rockshaft provided with arms, links connecting said arms to said feed clutches, a dashpot operatively connected to said rockshaft, a series coil armature operatively connected to said rockshaft, a series coil cooperating with said armature, series connections for said lamps including a resistance coil interposed between the said series coil and the first lamp of the series, and an adjustable resistance coil

in the circuit connection for the last lamp of the series.

3. The combination of an elongated cylindrically curved reflector mounted for tilting adjustment on an axis adjacent one edge thereof, a plurality of lamps each comprising a pair of bottom carbon supporting rods suspended within said reflector and provided with a lower carbon holder, top carbon holders provided with feed clutch rods disposed through said reflector, feed clutches coacting with said clutch rods on the outside of said reflector, a rockshaft provided with arms, links connecting said arms to said feed clutches, and a solenoid operatively connected to said rockshaft, said lamps being connected in series.

4. The combination of a reflector, a plurality of lamps each comprising a pair of bottom carbon supporting rods suspended within said reflector and provided with a lower carbon holder, top carbon holders provided with feed clutch rods disposed through said reflector, feed clutches coacting with said clutch rods on the outside of said reflector, a rockshaft provided with arms, links connecting said arms to said feed clutches, and a solenoid operatively connected to said rockshaft, said lamps being connected in series.

5. The combination of an elongated cylindrically curved reflector mounted for tilting adjustment about an axis adjacent one edge thereof, a plurality of arc lamps mounted on said reflector with their bottom carbons supported within the reflector, top carbon holders provided with feed means comprising feed clutches, a rockshaft operatively connected to said feed clutches, a dashpot operatively connected to said rockshaft, a series coil armature operatively connected to said rockshaft, a series coil cooperating with said armature, said lamps and series coil being connected in series with a resistance coil interposed between the series coil and one of the lamps, and a second resistance coil interposed in the circuit connection for the other lamp.

6. The combination of a plurality of arc lamps, top carbon holders provided with feed means comprising feed clutches, a rockshaft operatively connected to said feed clutches, a dashpot operatively connected to said rockshaft, a series coil armature operatively connected to said rockshaft, a series coil cooperating with said armature, said lamps and series coil being connected in series with a resistance coil interposed between the series coil and one of the lamps, and a second resistance coil interposed in the circuit connection for the other lamp.

7. The combination of an elongated cylindrically curved reflector mounted for tilting adjustment about an axis adjacent one edge thereof, a plurality of arc lamps mounted on said reflector with their bottom carbons sup-

ported within the reflector, said lamps being connected in series, top carbon holders provided with feed means comprising feed clutches, a rockshaft operatively connected to said feed clutches, a dashpot operatively connected to said rockshaft, and a solenoid operatively connected to said rockshaft.

8. In a lamp structure of the class described, the combination of a reflector, a plurality of lamps each comprising bottom carbon holders suspended within said reflector, top carbon holders disposed through said reflector and provided with feed means com-

prising clutch arranged on the outside of said reflector feed rods and coacting clutches, 15 a rockshaft operatively connected to said clutches, a dashpot operatively connected to said rockshaft, a solenoid operatively associated with said rockshaft, said lamps being connected in series, said rockshaft, dash- 20 pot and solenoid being mounted on the outside of said reflector, and a housing for said parts mounted on said reflector.

In witness whereof I have hereunto set my hand.

NORRIS E. GOODRICH.
